ARTERIAL EMBALMING METHOD AND
ARTERIAL EMBALMING FLUID

David H. Williams, Canfield, Ohio, assignor to
Robert C. Switzer, South Euclid, and Joseph L.
Switzer, Cleveland Heights, Ohio

No Drawing. Application April 13, 1945,
Serial No. 588,251

25 Claims. (Cl. 27—21)

This invention relates to improvements in the art of arterial embalming and in arterial embalming fluids. More particularly, this invention relates to a fluorescent arterial embalming fluid and a method of arterial embalming utilizing the phenomenon of fluorescence. It is to be understood that the following specification and claims relate to the phase of embalming known as "arterial embalming" and not to the phase known as "cavity embalming." This application is a continuation-in-part of the copending application of David H. Williams for Arterial embalming method and arterial embalming fluids, filed September 23, 1944, Serial No. 555,595, a continuation-in-part of the then copending application for Embalming fluid and method of using it, filed February 26, 1943, Serial No. 477,299.

When the present-day method of embalming by forcing a suitable embalming fluid through the circulatory system of a body was first developed about eighty years ago, the principal active ingredients in the embalming fluids were extremely effective arsenical compounds. The method has remained substantially unchanged, the improvements being in the embalming fluids. The chief fault of the early embalming fluids employing arsenical compounds was that the embalming fluids could mask murder by poisoning and, as a police measure, the appropriate regulatory boards and like governmental bodies have generally established strict regulations which practically limit the permissible active ingredients of embalming fluids to organic compounds such as formaldehyde. Another fault of early embalming fluids was that they tended to impart a leathery appearance which was unnatural and disturbing to the sensibilities.

The achievement of a thorough embalming by prior art methods and the use of prior art embalming fluids requires excellent judgment based on long experience. Heretofore, the only manner in which an expert embalmer could supplement his experienced judgment in determining the progress of an embalming was to detect the stiffening and hardening of the tissues due to the coagulating effect of the formaldehyde or like embalming medium. This required a subtle sense of touch and even the most experienced embalmer was never sure whether stiffened tissue was due to the embalming fluid or rigor mortis. Inexpert or hasty embalmers were wont to employ fluids having such a high concentration of formaldehyde that the tissues would be stiffened to a point of immobility; such practise was

undesirable, esthetically, because it imparted an unnatural statue-like appearance to the body and, practically, because the intense coagulating effect of the fluid closed the capillaries and actually prevented thorough embalming.

It is the object of this invention to provide a method of embalming which will permit the embalmer to have positive visual indication of the progress of an embalming by revealing the location of areas which are properly embalmed. It is another object of this invention to provide a method of embalming which will permit an embalmer to achieve thorough embalming while using a low concentration of an active embalming ingredient with the result that the embalmed tissues may be flexed and the body posed in a natural position.

A further object of this invention is to provide a fluorescent embalming fluid. A still further object of this invention is to provide a fluorescent embalming fluid in which the fluorescent ingredient dissolved is colorless or substantially so in visible light in order that the body embalmed therewith will appear natural when viewed in visible light.

It is an advantage of this invention that the method of embalming and the fluorescent embalming fluid will comply with all known regulations governing the practise of embalming.

The foregoing objects and advantages of this invention are achieved in general by employing an embalming fluid containing permissible active embalming ingredients, a fluorescent ingredient, and a mutual solvent for the active embalming ingredients and the fluorescent ingredient. As or after the fluorescent embalming fluid is forced through the circulatory system of the body being embalmed, the body is viewed under suitable fluorescogenous radiations, preferably filtered ultraviolet ranging between 3200 and 4000 Angstrom units in wave length. (Wherever examination under filtered ultraviolet is spoken of in this specification and claims, it is to be understood that such examinations are conducted in the substantial absence of extraneous visible light.) The progress of the embalming fluid through the body is revealed by the areas of the body which become fluorescent. By suitable massage, supplementary injections where necessary, and continued circulation of the embalming fluid, all external areas of the body may be rendered fluorescent; the emission of visible light from areas of the arms, legs, and the head indicates that the tissues of those members have been embalmed. The dissolved fluorescent ingredient

(hereinafter referred to as the "fluoragent") of the embalming fluid is preferably colorless in visible light, though, in some instances, a visibly colored fluoragent may be employed when the use of such a colored fluoragent will have a desirable cosmetic effect.

Other and further objects and advantages of this invention will be apparent from the following detailed description which is for an average 150 pound body which is neither excessively dehydrated nor dropsical.

The body may be washed in the usual manner preparatory to the embalming injections. Many antiseptic soaps employed for this purpose may leave a slightly fluorescent film; if such a soap 15 is employed, the body is thoroughly rinsed to remove traces of fluorescent soap which may interfere with indications in the actual embalming operation. The thoroughness of the rinsing operation is readily determined by examining the 20 body under filtered ultraviolet prior to commencing the injections of embalming fluid.

Also preparatory to the actual embalming operation, the body is preferably given the usual so-called "pre-injection" treatment, that is, suitable openings are made in the veins and arteries in order that the portions of the circulatory system being treated may be flushed with a suitable 25 so-called "pre-injection" fluid to remove blood, any clots which are present, and to open the capillaries. Such pre-injection fluids are available on the market and comprise, essentially, an aqueous carrier for anti-coagulants, such as sodium citrate or similar salts of organic acids, for example; the pre-injection fluid may also contain 30 a suitable wetting agent.

After the circulatory system is cleared by the pre-injection fluid, the circulatory system is injected with the fluorescent embalming fluid, the embalming fluid being supplied to the arterial 40 system from a reservoir through the usual injecting tube and the venous system being connected to a drain. Circulation of the embalming fluid may be forced in any suitable manner, preferably by providing the reservoir with sufficient head 45 which may be increased as occasion requires by the use of a syringe bulb.

The natural and/or artificial illumination of the embalming room is supplemented with a suitable source of filtered ultraviolet, preferably located above the embalming table. As injection 50 of the embalming fluid commences, the usual source of visible light is turned off or shuttered so that the room is in substantial darkness, sufficient illumination for the remainder of the embalming fluid injection operations being provided by the small amount of visible light which will leak through the ultraviolet filters and by the fluorescence of the embalming fluid.

As the embalming fluid is circulated, the diffusion of the fluid through the tissues is revealed as the fluid diffuses toward the skin. A portion of the incident ultraviolet will penetrate the surface of the body and, where the ultraviolet strikes the fluorescent embalming fluid, the energy of the ultraviolet is emitted as visible light. The circulatory system of the body is such that diffusion of the embalming fluid to the skin indicates that the underlying tissues (except in the thoracic and abdominal cavities) have likewise 60 been thoroughly penetrated, particularly when our fluorescent embalming fluid has a relatively low concentration of formaldehyde.

Any continued non-fluorescence of a portion of the body after the embalming fluid injection 75

has progressed immediately indicates to the embalmer that the circulatory system is impeded or blocked. The circulation to such non-fluorescent areas may be aided by suitable massage and manipulation and, in difficult cases, by localized injections. Thus, guesswork as to the necessity for localized injections is eliminated; this is a particular advantage in accident cases where the circulatory system is likely to be interrupted or impaired.

When the entire body surface has become fluorescent, a thorough embalming is indicated and the injection of the embalming fluid is stopped. As indicated above, the indications of this method are positive, except for the deep-seated organs in the abdominal and thoracic cavities; since the well-known cavity fluids are excellent for embalming these organs, the operation of embalming is completed by making direct trochar injections of cavity fluid in the thoracic and abdominal cavities; such treatment of these cavities is the phase of embalming known as "cavity embalming."

An excellent embalming fluid for use in the above described method is prepared by diluting one part of a fluorescent embalming fluid concentrate with fifteen parts of water. Illustrative examples of satisfactory fluorescent embalming fluid concentrates are as follows:

Example 1

	Parts by weight
Formaldehyde (gaseous)	25
Sodium nitrate	1
Sodium tetraborate	1
6 N sodium hydroxide solution	4

A phenol of the structural formula

2.25
Glycerine
5
Phenol
1
Citric acid
2
Water
70

The formaldehyde is dissolved in the major portion of the water and the balance of the above ingredients are dissolved in the remainder of the water. The two solutions are mixed and the alkalinity of the resultant concentrate is adjusted to pH 8 by addition of the organic acid or the sodium hydroxide. In the above embalming fluid concentrate, the formaldehyde, sodium nitrate, sodium tetraborate ($Na_2B_4O_7$), and phenol comprise the active embalming agents. The sodium hydroxide solution serves as a buffer for the acid ingredients and brings the fluid to the proper alkalinity. The phenol of the foregoing formula is the fluoragent; this fluoragent is soluble in alkaline aqueous solutions, and, in the final dilution of concentrate, is colorless under visible light. The glycerine serves as a softening agent and has somewhat of a dehydrating effect. The citric acid serves as an anti-coagulant for blood which may remain in the circulatory system. When the above concentrate (embalming fluids are usually sold commercially only in the form of concentrates) is suitably diluted, the resultant embalming fluid is colorless and has no cosmetic effect upon the embalmed body under visible light, though causing the surface of the body to exhibit

a bright blue-white fluorescence under filtered ultraviolet.

Example 2

	Parts by weight
Formaldehyde	25
Sodium nitrate	1
Sodium tetraborate	1
6 N sodium hydroxide solution	4.5

The mixed derivatives of dehydrothio para toluidine of the formulae:

Phenol	.25
Sodium lauryl sulphate	1
Tartaric acid	.05
Water	70

It will be noted that the above embalming fluid concentrate is substantially the same as that disclosed in Example 1, except for the substitution of a different fluoragent (the mixed derivatives, of the foregoing formulae, of dehydrothio para toluidine), a different organic acid, and the replacement of glycerine with sodium lauryl sulphate. The formaldehyde is dissolved in a major portion of the water, the balance of the ingredients are dissolved in the remaining water, the two solutions are mixed, and the alkalinity of the resultant concentrate is adjusted to pH 8, as in Example 1. Whereas the glycerine of Example 1 has somewhat of a dehydrating effect, the sodium lauryl sulphate is a powerful wetting agent and has a dehydrating effect which aids diffusion. The tartaric acid serves the same function as the citric acid in Example 1. The fluoragent in this example, the mixed derivatives, of the foregoing formulae, of dehydrothio para toluidine, is colored as a concentrated dye but, in the final diluted embalming fluid, is substantially colorless. Thus, when the above concentrate is suitably diluted, the resultant embalming fluid has no appreciable cosmetic effect on the body when viewed under visible light though imparting a powerful blue fluorescence to the embalmed body when viewed under filtered ultraviolet.

The foregoing examples are given by way of illustration and are not to be construed as limitative. For example, both of the concentrates given in Examples 1 and 2 are suitable for normal cases, but, due to the somewhat dehydrating effect of the glycerine in Example 1 and the hydrating effect of the sodium lauryl sulphate in Example 2, the concentrate of Example 1 is preferable for slightly dropsical cases and the concentrate of Example 2 is preferable for slightly dehydrated cases. It is, therefore, within the scope of this invention to adjust the concentrates so that specific concentrates for dropsical, normal, and dehydrated cases may be obtained.

Fluoragents which are colorless are substan-

tially so in the final diluted embalming fluid are preferably employed in order that no inappropriate cosmetic effects may be obtained; if cosmetic effects are desired, it is generally preferable that such effects be obtained by externally applied cosmetics or by the addition of the well-known appropriate cosmetic dyes to the concentrate or to the final diluted embalming fluid. It is within the scope of this method, however, to employ fluoragents which are not colorless and

which may have a cosmetic effect; the phthalein of the structural formula

is an example of such a fluoragent which, in proper proportions and on appropriate cases, will impart a suntan effect to the embalmed body. Effective proportions of the phthalein of the foregoing structural formula, for example, may range from three grains per gallon in a pre-injection fluid as injected into a body to one and one-half grains per gallon in a rather dilute embalming fluid injected into a body.

The proportion of fluoragent in the embalming fluid is dependent upon the ability of the fluoragent to impart the necessary fluorescence to the embalmed body. As shown in the foregoing examples, the power of specific fluoragents to impart the desirable fluorescence may vary according to the fluoragent employed. The proportion of the fluoragent in the above examples is suitable for the specific concentrates when the final diluted embalming fluids are used on normally pigmented Caucasian bodies. Due to the powerful light absorptive properties of melanin, heavily pigmented bodies of other races may require the use of embalming fluids in which the proportion of the fluoragent is increased.

It will be noted that if concentrates made according to the foregoing examples are diluted according to the proportions given, the formaldehyde index of the actual embalming fluids will be approximately that which is generally recommended. If a stronger formaldehyde concentration is desired, the proportion of formaldehyde may be increased or the concentrate may be diluted less. In order to obtain the greatest benefit from the method disclosed, however, the above concentrates are first diluted until the formaldehyde concentration is approximately one-half of one per cent (.5%). Such weak form-

aldehyde solutions are employed until one-half to one gallon of fluid has been injected. Thereafter, the injections are continued with the concentrate diluted according to the generally standard proportion of one part of approximately 25% formaldehyde concentrate to fifteen parts of water. Such practice may entail from five to seven one-half gallon injections of embalming fluid, as contrasted with the practice sometimes followed in making only four or five injections of a stronger solution. It should be borne in mind that the weaker formaldehyde concentrations recommended in the practice of this invention are no less effective as preservatives when such relatively weaker solutions are used in sufficient quantity. Because this invention permits positive indications of the extent of diffusion of the embalming fluid, such weaker solutions are ultimately better preservatives in that they allow the embalmer to avoid the possibility of so rapidly coagulating the tissues that thorough diffusion of the embalming fluid is prevented. A body embalmed by the preferred practice under this invention is not rigidly "set up" by the embalming and may thus be posed in a natural position.

It should be noted that the fluid used in the above mentioned "pre-injection" treatment is not described as being fluorescent. Since the purpose of the "pre-injection" treatment is principally to aid the subsequent embalming fluid injection and since the fluorescent embalming fluid reveals the extent of its diffusion, use of a fluorescent "pre-injection" fluid would be superfluous, to an extent. If a fluorescent pre-injection fluid is desired, however, it is within the scope of this invention to incorporate fluoragents in quantities and kind similar to those employed in the actual embalming fluids. If fluorescent pre-injection fluids are employed, it is recommended that one select a fluoragent which fluoresces with a color distinctive from that of the fluorescent embalming fluid, in order to prevent the residual fluorescence of the pre-injection fluid from being mistaken for the fluorescence of the embalming fluid. Since the fluorescent colors of fluoragents are additive, contrast between the fluorescent embalming fluid and the pre-injection fluid is often difficult to obtain and the use of a fluorescent pre-injection fluid is, accordingly, generally discouraged.

It is also within the scope of this invention to employ only a fluorescent pre-injection fluid, relying upon the fact that thorough diffusion of the pre-injection fluid will generally be followed by a similar diffusion of the embalming fluid. Since the fluorescent indications of this variation of the invention are not positive indications of the extent and degree of embalming, this practice is likewise generally discouraged. Other variations of this invention, which may be useful in specific instances, will occur to those skilled in the art. For example, this invention has been described in connection with the preparation of human bodies for burial; this invention is also useful in the preservation of cadavers, parts of bodies, and organs for use in the medical and teaching professions. The term "bodies" as employed in the appended claims is, therefore, to be understood to include parts and organs of bodies, both of humans and of lower orders of creatures.

What is claimed is:

1. In the embalming and preservation of bodies, the steps of injecting into a body to be preserved a fluid containing a fluoragent and then

10 inspecting the body under fluorescigenous radiations to detect the extent of diffusion of the injected fluid by the fluorescence of said fluid.

5 2. In the embalming and preservation of bodies, the steps of injecting into a body to be preserved a fluid containing an active embalming agent and a fluoragent, subjecting the body to fluorescigenous radiations, and observing the extent of diffusion of the active embalming agent by the fluorescence at the surface of said body.

15 3. The method of embalming a portion of a body comprising the steps of injecting a fluorescent embalming fluid, subjecting the portion to be embalmed to fluorescigenous radiations, and continuing injection until all the surface of the portion to be embalmed becomes fluorescent.

20 4. A method of detecting the diffusion of an injected embalming agent within a body by injecting a fluoragent and inspecting the body under fluorescigenous radiations to detect the extent of diffusion of the fluoragent by the fluorescence of the portion of the fluoragent which has diffused to the surface of the body.

25 5. In the art of embalming, the method of preventing non-embalming of surfaces desired to be embalmed comprising the steps of subjecting the member to be embalmed to fluorescigenous radiations and circulating a fluorescent embalming fluid within the member until all the surfaces desired to be embalmed become fluorescent.

30 6. The method of embalming a body consisting of the normal injection therein of an embalming fluid incorporating a substance capable of fluorescence, subjecting the body to ultraviolet light and regulating the amount of fluid injected through visual guidance by the fluorescent effect of the penetration and diffusion of the fluid in the tissues of the body.

35 7. The method of embalming a body comprising the steps of injecting an ultraviolet responsive fluorescent embalming fluid, subjecting the body to ultraviolet light, observing the penetration and diffusion of the said fluid on the surfaces of the said body and assisting the circulation of the said fluid to the areas indicated by lack of fluorescence.

40 8. The method of embalming a body comprising the steps of subjecting the body to pre-injection treatment to clear the circulatory system of the body, injecting into the circulatory system of the body an embalming fluid containing in solution an active embalming ingredient and a sufficient quantity of a fluoragent to render the fluid noticeably fluorescent when the fluid is diffused in capillaries at the surface of the body, inspecting the body under filtered ultraviolet, and forcing circulation and diffusion of the fluid into portions of the body under non-fluorescent areas of the surface of the body until such areas become fluorescent.

45 9. A method as defined in claim 1 in which said fluoragent is diluted until the fluoragent exhibits substantially no color in visible light in order to avoid a cosmetic effect due to the fluoragent.

50 10. A method as defined in claim 4 in which said fluoragent is diluted until the fluoragent exhibits substantially no color in visible light in order to avoid a cosmetic effect due to the fluoragent.

55 11. A method as defined in claim 5 in which said fluoragent is diluted until the fluoragent exhibits substantially no color in visible light in order to avoid a cosmetic effect due to the fluoragent.

60 12. A method as defined in claim 8 in which

said fluoragent is diluted until the fluoragent exhibits substantially no color in visible light in order to avoid a cosmetic effect due to the fluoragent.

13. A method as defined in claim 8 in which said pre-injection treatment includes the step of injecting into the circulatory system of the body a pre-injection fluid containing a dissolved anti-coagulant and a fluoragent.

14. The method of embalming a body comprising the steps of circulating a fluorescent capillary wash fluid through the members of the body which are to be embalmed, subjecting the body to fluorescigenous radiations, assisting circulation to non-fluorescent areas of the portions to be embalmed, and then circulating a preserving fluid through the portions to be embalmed.

15. A method as defined in claim 8 in which said pre-injection treatment includes the step of injecting into the circulatory system of the body a pre-injection fluid containing a dissolved anti-coagulant and a fluoragent selected to fluoresce with a fluorescent color different from the fluorescent color of the fluoragent in the embalming fluid.

16. A method of embalming a body comprising the steps of subjecting the body to a pre-injection treatment by flushing the circulatory system with a pre-injection fluid containing a dissolved anti-coagulant and an ultraviolet-responsive fluoragent, inspecting the body under filtered ultraviolet, assisting circulation of the pre-injection fluid until the surface of all portions of the body which are to be embalmed become visibly fluorescent, and then injecting an embalming fluid into the circulatory system which has been flushed with the pre-injection fluid.

17. The method of embalming a body comprising the steps of circulating through a body an ultraviolet-responsive fluorescent embalming fluid through the veins and arteries and capillaries of the body, subjecting the body to ultraviolet light, the fluorescence indicating the circulation and diffusion of the said fluid in the tissues of the said body, and the further step of assisting the circulation of the said fluid to the areas indicated by lack of said fluorescence.

18. A method of embalming bodies comprising the steps of injecting into the circulatory system of a body an embalming fluid containing a dissolved ultraviolet-responsive fluoragent and formaldehyde, said fluoragent being in sufficient concentration to emit visible light through the surface of said body when said body is subjected to ultraviolet and said formaldehyde being in a concentration of less than one per cent, inspecting the body under filtered ultraviolet and assisting circulation of the injected embalming fluid to non-fluorescent areas of said body, and increasing the concentration of formaldehyde above one per cent as injection of said embalming fluid is continued.

19. A fluid for use in embalming a body comprising a fluoragent and an aqueous solvent in

5 which said fluoragent is dissolved, in sufficient concentration to indicate visibly through the skin the penetration of the fluid within a body when the fluid is injected into a body and the body is subjected to fluorescigenous radiations, said fluoragent being substantially colorless under visible light in the dilution in which said fluid is injected in the body.

10 20. An embalming fluid comprising a solution of a preserving agent and a fluorescent substance, in sufficient concentration to indicate visibly through the skin the penetration of the fluid within a body when the fluid is injected into a body and the body is subjected to fluorescigenous radiations.

15 21. A capillary wash fluid for use in embalming comprising a solution of an anti-coagulant and a fluorescent substance, in sufficient concentration to indicate visibly through the skin the penetration of the fluid within a body when the fluid is injected into a body and the body is subjected to fluorescigenous radiations.

25 22. An embalming fluid concentrate containing a water-soluble fluoragent, formaldehyde, and water, said fluoragent being in such concentration with respect to the concentration of formaldehyde that said fluoragent will be fluorescent through the surface of a body when said concentrate is diluted until the concentration of formaldehyde is less than two per cent and more than one-half of one per cent and injected into a body and said body is examined under filtered ultraviolet, said fluoragent being substantially colorless under visible light when said concentrate is diluted for injection into a body.

30 35 23. An embalming fluid comprising a solution of formaldehyde and a fluorescent substance in sufficient concentration to indicate visibly through the skin the penetration of the fluid within a body when the fluid is injected into a body and the body is subjected to fluorescigenous radiations.

40 45 24. An embalming fluid comprising an aqueous solution incorporating therein formaldehyde and including a phthalein of the structural formula

at a ratio between 1½ and 3 grains per gallon.

25 60 65 26. An embalming fluid comprising water, formaldehyde, and a substantially colorless water-soluble fluoragent in sufficient concentration to indicate visibly through the skin the penetration of the fluid within a body when the fluid is injected into a body and the body is subjected to fluorescigenous radiations.

DAVID H. WILLIAMS.
